Primary Examiner — Zenia Bennett(74) *Attorney, Agent, or Firm* — Flynn, Thiel, Boutell & Tanis, P.C.(57) **CLAIM**

The ornamental design for a light fixture base, as shown and described.

DESCRIPTION

FIG. 1 is a top and left side isometric view of a light fixture base embodying my new design;

FIG. 2 is a top view thereof;

FIG. 3 is a cross sectional view taken along the line 3-3 of FIG. 2;

FIG. 4 is a cross sectional view taken along the line 4-4 of FIG. 2;

FIG. 5 is a left side view, the right side view being identical thereto;

FIG. 6 is a front side view thereof, the rear side view being identical thereto; and,

FIG. 7 is a bottom view thereof.
